ELECTRIC COMMUTATOR OR THE LIKE
HAVING BRUSHES CONSISTING OF CONDUCTIVE LIQUID JETSJulius Frederik Georg Poul Hartmann,
Copenhagen, DenmarkApplication May 3, 1933, Serial No. 669,092, and
in Germany May 21, 1932

8 Claims. (Cl. 171—321)

This invention relates to an electric commutator with movable segments and with brushes constituted by conductive liquid jets, for instance mercury jets.

5 It is known that in rotating commutators for electric machines the use of conductive liquid jets as brushes makes it possible amongst other things to obtain a very substantial increase of the maximum permissible voltage between commutator segments. However, here the formation of sparks gives rise to difficulties in a similar manner as in many other types of commutators. The invention now has for its object to eliminate objectionable effects of the commutation arcs 10 which according to the invention is attained by the provision of one or more knives of conducting material following the movement of the segments and insulated therefrom, which knives serve to cut the brush jets in such a manner that 15 the commutation arcs are formed mainly between liquid surfaces only. If the knives are made from a material having a high melting point, such as tungsten, they are not at all injured by the sparks or arcs, i. e. the commutator 20 is practically not worn, and thus the commutation arcs may be disregarded.

A further feature of the invention consists in that adjacent ends of the segments are mutually displaced in the direction of movement of the jet 30 particles, and that the knife is positioned in advance of or in the space thus formed between such adjacent ends of consecutive segments, the knife being preferably adjustable.

According to still another feature of the invention, each brush is made up from two electrically connected conductive liquid jets which are mutually displaced both in the direction of movement of the segments and in a direction 35 perpendicular thereto, whereas the knife which is preferably adjustable is so arranged as to cut that jet only which is passed as the last one by the knife.

The invention may be applied not only to rotating electric commutators of general types and the like but also to electric apparatus with movable segments or other contact pieces which in a wider sense may be considered as commutator-like devices, for instance to cell switches for 40 storage batteries.

On the accompanying drawing two embodiments of a rotating electric commutator according to the invention are shown diagrammatically by way of example.

55 Figure 1 is an end view of one embodiment,

Figure 2 shows a longitudinal section through the same,

Figure 3 shows a detail of the same on a larger scale,

Figures 4 and 5 is an elevation and an end view respectively, of part of the second embodiment, and

Figure 6 is a diagram illustrating the setting of the knife.

The direction of rotation of the segments and the knives which move synchronously is indicated by arrows.

The commutator shown in Figures 1 and 2 comprises a circular row of commutator segments E₁, E₂, E₃—E₆ which co-act with two approximately straight conductive liquid jets J₁ and J₂ issuing from stationary nozzles N₁ and N₂ respectively and serving as brushes. Adjacent ends of the neighboring segments are, as shown, mutually displaced in the direction of movement 65 of the jet particles, i. e. radially, and the outermost end furthermore slightly overlaps the adjacent innermost end.

In or immediately in advance of the space thus formed a conductive knife is arranged. 80 These knives are designated by W₁, W₂, W₃—W₆ respectively; as above mentioned they move along together with the segments, but they are electrically insulated from the latter. The knives are preferably made of tungsten or a 85 similar refractory material, and each knife is welded onto a shank H of steel which is rigidly secured to a circular disc K of insulating material mounted on the shaft D of the commutator.

Each segment has a lateral flap A which by a screw B is rigidly secured to a second disc C of insulating material. The two insulating discs are spaced by a ring M, and both of them are clamped in position on the shaft D between a clamping nut L and a head P on one 90 end of the shaft. The knives preferably are adjustable circumferentially in order that the time during which consecutive segments remain short circuited by the jet may be regulated.

For this purpose the knife carrying disc K after 95 loosening of the nut L may be turned somewhat relative to the segment carrying disc C whereupon both discs are again clamped between nut L and head P. Also the knives may be adjusted individually by being turned around the longitudinal axis of the knife, which is easily understood from Figure 2.

By the cutting of the brush jet both of the 100 commutation arcs which in the very first moment are formed between the edges a and b 110

(Figure 3) at the back surface of the knife and the separated jet portions respectively practically instantaneously are united to form a single arc F the base points of which are found on the two jet strings respectively.

Thus the only effect is that the conductive liquid is evaporated which, of course, is of no consequence since at each commutating operation a new sparking gap is formed.

10 In Figures 4 and 5 the commutator segments E_1 , E_2 , E_3 are circular and concentric with the shaft D of the commutator. The latter is provided with two diametrically oppositely arranged brush devices one of which is shown only, as 15 Figures 4 and 5 illustrate one half of the commutator only. This brush device consists of two, preferably adjustable, nozzles N_1 and N_1' which are mutually displaced both in the direction of movement of the segments and in the direction 20 of the commutator axis. From each of these nozzles a conductive liquid jet J_1 and J_1' respectively issues. The jets are electrically connected with each other and thus they form together a bow-like brush. In the position of 25 the commutator shown in Figures 4 and 5 the segments E_1 and E_2 are shortcircuited by the jets. The short-circuiting lasts until the jet J_1 is cut by the knife W_1 which is arranged axially and outside the segments and rotates with the latter. The duration of the 30 short-circuiting thus may be varied by adjusting this knife. Furthermore in Figures 4 and 5 the knives W_1 , W_2 and the segments are mounted on the shaft D by means quite similar to those shown in Figures 1 and 2, alike details being designated by the same reference characters. Thus the knives may also here be 35 adjusted circumferentially by relative turning of the discs K and C.

40 In order to completely attain the effect aimed at by the invention it is desirable to so form and adjust the knife cutting the brush jet that both of the jet portions separated by the knife remain in contact with the same during the 45 entire period of cutting.

It is thus a condition that the knife must be adjusted into an inclined position relative to the axis of the jet in such a manner that the direction of the relative velocity V_r of the jet 50 particles falls within the contour of the cross-section of the knife, as will appear from the velocity diagram shown in Figure 6, wherein V_j and V_w represents the absolute velocity of the jet particles and of the knife W respectively.

55 In the commutator constructed according to the present invention at each brush place more jets connected in parallel may naturally be used. Also the jets may be cut at each space between segments by two or more knives instead 60 of by one knife only.

Having thus fully described my invention I

claim as new and desire to secure by Letters Patent:

1. An electric commutating or switching device, comprising a plurality of movable segments, means for producing at least one conductive liquid jet co-acting with said segments and serving as a brush, and a knife of conductive material following the movement of the segments and insulated from the latter, said knife being so arranged as to cut said liquid jet substantially in the moment when it short-circuits two consecutive segments. 80

2. The electric commutating or switching device of claim 1, in which said knife is adjustable. 85

90

3. A rotating electric commutator, comprising a circumferential series of rotating spaced segments, means for producing conductive liquid jets serving as commutator brushes and co-acting with said segments, and a conductive cutting device arranged in the neighbourhood of the space between each pair of consecutive segments, said cutting device rotating together with the segments and being arranged to cut the said liquid jets in such a manner that the commuta- 100

105

4. The rotating electric commutator of claim 3, in which said cutting device is adjusted circumferentially. 105

5. An electric commutator or the like comprising a plurality of movable segments, means for producing conductive liquid jets co-acting with said segments, adjacent ends of consecutive segments being mutually displaced in the direction of movement of the jet particles, and a knife of conductive material following the movement of said segments and arranged substantially in the space thus formed between such adjacent ends of consecutive segments, which 110

115

knife serves to cut the liquid jets. 115

6. An electric commutator or the like, comprising a plurality of movable segments, stationary brushing devices co-acting with said segments and consisting each of means for producing two electrically interconnected conductive liquid jets which are mutually displaced both in the direction of movement of the segments and in a direction perpendicular thereto, and a knife of conductive material following the movement of the segments and insulated therefrom, which knife is so arranged as to cut that jet only of said brushing device which is passed as the last one by the knife. 120

7. The electric commutator or the like of 120

claim 5, in which said knife is adjustable. 125

8. The electric commutator or the like of claim 6, in which said knife is adjustable. 130
